United States Patent

Des. 235,096

Patented May 13, 1975

235,096

ASPHALT PLANT TOWER OR SIMILAR ARTICLE

Frederick A. Mohr, Signal Mountain, Tenn., assignor to
Astec Industries, Inc., Chattanooga, Tenn.

Filed Dec. 17, 1973, Ser. No. 425,337

Term of patent 14 years

Int. Cl. D25—03

U.S. Cl. D13—1 R

FIG 2

FIG 1

FIG. 5

FIG. 4

FIG. 3

FIG. 1 is a perspective view of an asphalt plant tower embodying the design of my invention;

FIG. 2 is a left side elevation view of the asphalt plant tower;

FIG. 3 is a front elevation view of the asphalt plant tower;

FIG. 4 is a right side elevation view of the asphalt plant tower; and

FIG. 5 is a rear elevation view of the asphalt plant tower.

I claim:

The ornamental design for an asphalt plant tower or similar article, as shown.
